UNITED STATES PATENT OFFICE.

HOWARD L. THOMAS, OF CIRCLEVILLE, OHIO.

FENCE POST.

Application filed September 28, 1925. Serial No. 59,307.

This invention relates to improvements in fence posts and has for its prime object to provide a device of this character adapted to readily engage and support in position a wire fence or the like.

Another object of the invention is to provide a fence post of durable yet comparatively simple construction designed to permit convenient attachment of fence structures of various types.

Another object of the invention is the provision of a fence supporting post which may be manufactured and sold at a reasonable cost.

Other objects and advantages of the invention will become apparent as the description progresses.

In the accompanying drawing forming a part of this specification and in which like numerals are employed to designate corresponding parts throughout the same:

Figure 1 is a front elevation of a fence post constructed in accordance with my invention shown in operative position.

Figure 2 is a side elevation of the same, Figure 3 is an enlarged top plan view,

Figure 4 is a transverse sectional view taken on the line 4-4 of Figure 2, and

Figure 5 is a perspective view of one of the supporting elements.

In the drawing, wherein for the purpose of illustration is shown the preferred embodiment of my invention, the numeral 10 generally designates the body of my improved post, this body being of channel formation or U-shape in cross section so as to provide a transverse back plate 11 and a pair of parallel side plates or flanges 12.

As will be readily seen with reference to

Figures 1 and 2, the lower portion of the transverse back plate 11 is of tapered formation at the lower end to provide a driving point 13 adapted to normally extend into the ground for supporting the post.

The lower extremities of the side plates or flanges 12 are cut away in angular formation, as at 14, and terminate substantially above the lower extremity of the back plate so as to facilitate the operation of driving

the post into the ground. In order to properly engage a fence and retain same in a vertical position, the post is provided with suitable engaging means comprising, in the present instance, a plurality of V-shaped notches 15 formed in the outer longitudinal edges of the flanges 12, these notches being

of any desirable number and formed so as to accommodate the common forms of fence strands.

Due to the substantial weight of the conventional type of fence construction and the necessity for firmly retaining the posts in upright position, it is considered advisable to equip the posts with suitable bracing means embodying, in the present instance, a transversely extending plate 16 firmly secured to the transverse back plate 11 by bolts or rivets in a slightly elevated position relative to the point of the post, this plate being preferably cut at an obtuse angle at its lower extending edges, as at 17, to enable same to be conveniently mounted in position in the ground. This plate is provided at its upper edge adjacent the side plate of the post with a vertical slot, not shown, extending to the longitudinal center line of the plate for engagement with a complementary brace plate 18 having a central vertical slot 19 engageable therewith for convenient connection of these members.

In assembled position, it will be obvious with reference to Figures 1 and 4, that the brace plates 16 and 18 intersect so as to form a substantial bracing foundation for the post. This structure will serve to materially strengthen the vertical position of the posts and reduce the possibility of the posts being torn down by excessive weight upon the fence or by the elements. The foregoing construction comprising the channel shape post 10 and brace plates is preferably formed of light metal so as to permit of convenient transportation and erection.

As is readily apparent from Figure 1 of the drawing, the transverse back plate 11 of the post structure is provided with a pair of circular openings or apertures 20, one such opening being formed adjacent the upper extremity of the plate and another in the lower portion immediately above the ground line of the post. These openings are arranged for receiving an engaging member 21 preferably formed of a round metallic rod comprising a longitudinal body portion bent at right angles at the upper extremity to provide a securing arm 22, the end of this arm being externally screw threaded, the purpose of which will become apparent as the description progresses. The lower extremity of the securing member 21 is bent inwardly to provide an offset substantially parallel extension lug 23 adapted

2
to contact with the rear face of the transverse base plate 16.

As has been previously intimated, the angular projections of the securing member extend through the openings 20 formed in the transverse back plate 11 and the member is arranged so as to be adjustable relative to the outer notched edges of the flanges and is normally positioned therebetween. Referring now more particularly to Figure 2 of the drawings, it will be noted that the fastening rod 21 in its operative position in engagement with a fence, will extend vertically in alignment with the extension edges of the flanges 12, the inner edge of the rod body being preferably in transverse alignment with the inner edges of the V-shaped notches formed in the flanges so as to contact with the wire strands of the fence. This rod is securely held in position in firm engagement with the fence by means of a nut 24 threadedly mounted on the screw threaded end of the upper arm of the fastening rod and adapted to bear against the back plate of the post.

In use, the posts are first firmly driven into the ground at predetermined intervals and the fastening rods 21 held in an outward angular position disengaged from the posts to permit the fence strands to be inserted in the V-shaped notches formed in the post flanges. After the fence wires have been inserted in their proper notches the fastening rod 21 is moved in an angular arc into engagement with the post, inserting the upper horizontal arm of the rod through the upper opening. The nut 24 is then firmly threaded upon the arm 22 until the proper tension has been acquired and the fence will be thus securely retained in position.

It is to be particularly noted that my im-

proved device has been designed with the intention of providing a durable yet simple post which may be placed upon the market at a reasonable cost, yet will withstand the 45 severe usage to which devices of this character are subjected. The device possesses many advantages over the well known types of posts now in common use, as the construction will readily permit the device to 50 be erected with facility and will permit the fence wires to be conveniently assembled or disassembled.

It is to be understood that the form of my invention shown and described is to be taken as the preferred example of the same, and that various changes as to the shape, size, and arrangement of parts may be resorted to without departing from the spirit of the invention or the scope of the subjoined 60 claim.

Having thus described my invention, I claim:

A fence post structure comprising a channel shaped body provided at the edges of its side flanges with notches, the said body being provided at its back plate and in the vicinity of its opposite ends with apertures, plates intersecting at right angles adapted to be anchored in the earth and against 70 which the body may bear adjacent the point of intersection of the said plates, and a fastening rod having angularly disposed end portions passing through the said apertures, a tightening nut screwed upon one of the 75 angularly disposed end portions of the rod and the other end portion of the rod having an offset extremity engageable over the edge portion of one of the anchoring plates.

In testimony whereof, I have affixed my 80 signature.

HOWARD L. THOMAS.
